UNITED STATES PATENT OFFICE

ERNEST C. FLATMAN, OF BIRMINGHAM, MICHIGAN

WAGON

Application filed November 29, 1929. Serial No. 410,556.

The present invention relates broadly to carts, wagons, cars or the like having a novel construction, which in toy form is of educational value for children by enabling them to assemble and disassemble the parts in a manner which will arouse latent creative or mechanical tendencies.

The invention has for its main object the provision of a cart or wagon of very simple and durable construction having few parts which may be detachably fitted together without the aid of bolts, nuts or screws and which, when so assembled, will co-operate with each other for maintaining the structure in assembled relation.

A further object of the invention is the provision of a cart, wagon or car body structure which can be readily knocked down or disassembled so that its complemental parts may be compactly arranged to occupy a very small space for storage or packing and shipping purposes.

The invention further resides in the sundry details of construction, combination and arrangement of parts hereinafter more fully described and pointed out in the appended claims.

In the drawings which show the preferred embodiment of the device as at present devised:—

Fig. 1 is a perspective view of a cart or wagon constructed in accordance with the invention; and

Fig. 2 is a perspective view of the invention with all of the parts disassembled but positioned relative to each other indicating the method of assembly.

Referring in details to the drawings in which like characters denote similar and like parts throughout the several views, 10 denotes the wagon bottom consisting of a substantially flat piece of suitable material having its side edges recessed or cut away at 11 so as to provide outwardly extending projections 12 on opposite sides of said recess. The sides of the wagon are provided by members 13 and 14 also formed from substantially flat pieces of board or sheet material. The side members 13 and 14 are identical in con-

struction and therefore for convenience only one will be described in detail.

The side member 13 may be of any suitable length according to the style and type of the wagon or cart being designed, and is of a width which will permit the side member to extend for a distance above and below the bottom 10 of the wagon body. The ends of the side members are formed with slots 15 extending inwardly from the end edges and are of a width and length to receive and fittingly accommodate the projections 12 on the bottom 10. The slots 15 extend longitudinally of the side members and are positioned, preferably, at an intermediate point between their longitudinal edges. Thus, it will be seen, particularly from Fig. 2 of the drawings, that when the projections 12 are extended into the slots 15, the wagon body is substantially formed.

End members 16 are provided to hold the side members in assembled position with respect to the bottom of the wagon body. These end members are of a length to extend transversely across the wagon body and are slotted at their end portions, as at 17, the slots extending inwardly and transversely of the end members from their lower longitudinal edge. The side members of the wagon body are also provided at their end portions with slots 18 extending from the upper longitudinal edges of the side members in a transverse direction, but on a slight angle so that said slots 18 in each side member will converge downwardly toward each other. The slotted portion of the end members 16 engage the slotted portions of the side members 13 and 14 to form interlocking joints x, as clearly shown in Fig. 1, which prevent the side members 13 and 14 from becoming disassembled or disengaged from the bottom 10.

Manifestly, the bottom, side walls and end members of the body structure are firmly and tightly secured together as the side members 13 and 14 are held against longitudinal shifting movement with respect to the bottom 10 by the projections 12 and the shoulders provided by the cut away portion 11, and the end members prevent lateral movement of the side members; and, further, the projections

12 together with the end members prevent tilting movement of the side member with respect to the bottom member. However, upon merely disengaging the end members 16, 5 the entire structure can be readily knocked down or disassembled.

The wagon body thus constructed may be supported by wheels in any suitable manner. For toy purposes, one means is shown 16 for mounting the wheels. As a cart, the body may have but two wheels, one on opposite sides of the body, but as a car or wagon, the body may have four wheels. These wheels 20 are shown as mounted directly to the side members 13 and 14, each by means of a short-headed axle pin 21 which has its unheaded end extending through an opening 22 in the side members 13 and 14 at points below the slots 15 therein and, consequently, below 25 the wagon bottom 10.

The device may be drawn in any suitable fashion but is here shown as being drawn by a tongue 23 connected to a bifurcated portion 24 formed, or otherwise provided, at one 23 end of the wagon bottom 10, through means of a cotter pin or other fastener 25. Cotter pins 26 may be provided for the inner ends of the axle pins 21.

It will thus be seen that the wagon body 30 thus constructed is of very substantial and durable character and is firmly and securely held together by the inter-engaging and the interlocking of grooved and tongued portions of the complementary parts thereof, requiring no nails or other fastener members, and which permits the wagon or cart to be readily disassembled and packed away in a small space.

It will also be readily understood that the 40 cart or wagon thus described may have other utilitarian purposes than that of a toy. It is readily adapted and useful as an automobile trailer, or for other like uses, and in which event, it may be desirable to substitute a transverse shaft for the axle pins 21.

A cover 27 for the cart or wagon may be provided, and in this connection the end members of the wagon body are provided with top bows 28, the ends of the bows being 50 removably inserted in openings or sockets in or on the end members. The top or canopy is stretched between the bows or is formed with suitable hems or pockets 29 in which the bows extend. When the end members 55 are in assembled position the canopy will be stretched taut and the tension thus provided will tend to further bind the end members in the slots 17 of the side members 13 and 14, which, in the case of a toy, will prevent the 60 hood or top 21 and the end members from falling out of assembled position, if the device is turned up-side-down.

It will of course be understood that the material from which the bottom, side members 65 and end members are made has the neces-

sary thickness so as to provide the proper bearing surface between the inter-engaged parts in order to maintain the parts in the desired relationship. When thin sheet metal is used, the parts may be flanged, bent or 70 rolled for this purpose.

In this specification and the annexed drawings, the invention is disclosed in the form in which it is considered to be the best, but the invention is not limited to such form 75 because it is capable of being embodied in other forms; and it is to be understood that in and by the claims following the description herein it is intended to cover the invention in whatever form it may embody within the 80 scope hereof.

Having thus described my invention, what I claim is new and desire to secure by Letters Patent of the United States is:

1. A device of the character described comprising a bottom member having outwardly extending side projections, side members having openings therein to receive said projections, end members having slotted end portions straddling and connecting said side members, and detachable wheels on said side members below said bottom member. 85

2. A device of the character described comprising a bottom member having outwardly extending side projections, side members having openings therein to receive said projections, end members having slotted end portions straddling and connecting said side members, detachable wheels on said side members below said bottom member, a hood for 90 said body comprising a cover, bow members for holding said cover extended, and means on the end members for detachably receiving the ends of said bow members, whereby said cover is stretched over the body member. 95

3. A device of the character described comprising a bottom member having outwardly extending side projections, side members having openings therein to receive said projections, end members having slotted end portions straddling and connecting said side members, detachable wheels on said side members below said bottom member, and draft means connected with said bottom member. 100

4. A device of the character described comprising a substantially flat bottom member having outwardly extending side projections, side members having slots therein to detachably receive said projections, transverse end members having slots in the end portions thereof straddling and detachably connecting said side members, and traction wheels mounted on said device. 110

5. A device of the character described comprising a substantially flat bottom member having outwardly extending projections on its side edges, side members having openings therein to detachably receive said projections, end members having slots in the end portions thereof straddling and detachably connecting 120 125 130

said side members, the side members having corresponding slots to receive corresponding portions of the end members, whereby an interlocking joint is provided, and traction wheels for the device.

5 6. A device of the character described comprising a substantially flat bottom member having projections on its side edges, vertical side members to abut against the side edges of 10 said bottom member and having openings therein to detachably receive said projections, vertical end members extending transversely of said bottom member and having slotted end portions straddling and detachably engaging 15 said side members for holding the latter against lateral movement with respect to said bottom member, and wheels on said side members, and draft means for the device.

7. A device of the character described comprising a body member including a substantially flat horizontal bottom member having its side edges recessed at intermediate points to provide outwardly extending projections, vertical side members having longitudinal 25 slots intermediate therewith to detachably receive said projections, transverse end members having slotted end portions adapted to detachably receive and fit over said side members, the side members having correspondingly slotted portions to receive the corresponding portions of the end members, whereby an interlocking joint is provided; and detachable wheels on said side members below said bottom member.

35 8. A device of the character described comprising a body member including a substantially flat horizontal bottom member having its side edges recessed at intermediate points to provide outwardly extending projections, 40 vertical side members having longitudinal slots therein intermediate therewith to detachably receive said projections, transverse end members having slotted end portions adapted to detachably receive and fit over 45 said side members, the side members having correspondingly slotted portions to receive the corresponding portions of the end members, whereby an interlocking joint is provided; said side members having openings 50 therein below said bottom member, axle pins detachably mounted in each of said openings in said side member, and a traction wheel rotatable on each of said pins.

9. A device of the character described in 55 claim 7, further characterized by a hood for said body comprising a cover, bow members for holding said cover extended, and means on the end members for detachably receiving the ends of said bow members, whereby, when 60 said cover is stretched taut over the body, an added binding engagement is caused between said end and side members.

10. A vehicle body of the character described comprising parallel side members, 65 traction wheels on and supporting said side

members, a horizontal bottom member disposed between the side members and detachably secured thereto for maintaining the side members in spaced relation, and end members detachably engaging the side members 70 and transversely connecting the same to maintain the side members in position.

11. A vehicle body of the kind described comprising a bottom member, substantial parallel side members, complementary portions on said bottom and side members having means interengaging to detachably connect and support the parts relative to each other, and body end members extending transversely of the body and detachably interlocked 75 with the side members and connecting the same, and traction wheels for the body.

In testimony whereof I have hereunto set my hand.

ERNEST C. FLATMAN.
